KONRAD W. JURISCH AND JOHN H. LEWIS, OF WIDNES, ENGLAND, AND
WILHELM R. PROELL AND CARL J. SCHAROWSKY, OF DRESDEN,
SAXONY.

INJECTOR-ENGINE.

SPECIFICATION forming part of Letters Patent No. 233,354, dated October 19, 1880.

Application filed July 8, 1880. (No model.)

To all whom it may concern:

Be it known that we, Dr. KONRAD WILHELM JURISCH and JOHN HENRY LEWIS, both of Widnes, England, and Dr. WILHELM RUDOLPH PROELL and CARL JOSEPH SCHAROWSKY, both of Dresden, Saxony, have invented an Improved System of Steam-Engines in which a partial reutilization of the waste steam takes place, of which the following is a specification.

Our invention relates to a system of steam-engines in which the waste steam is partly returned to the steam-boiler from which the engine is supplied, such return being effected by means of an injector or other apparatus adapted for the purpose, and worked by steam from a high-pressure boiler.

This system is represented on the annexed sheet of drawings by Figure 1, whereas Fig. 2 shows an auxiliary part.

A is the high-pressure boiler, in which the steam is generated for working the engine D as well as the injector Z. The engine is, however, not supplied directly from this boiler, but from a boiler, B, connected in a special manner with the former, and containing steam which is maintained at a lower pressure than the steam in A. The steam from B passes by pipe I into the cylinder D, and, after having acted within the same in the ordinary manner, it is exhausted into the reservoir S. From the latter the injector (or steam-jet apparatus) Z, worked by steam from A, draws a part of the exhaust-steam and delivers it, together with the steam from A, into the boiler B, the remaining portion of exhaust-steam passing off from S by the valve b into the outer air or into a condenser.

The high-pressure boiler is, by preference, a sectional or tubular safety-boiler; but instead of such, a boiler of other construction adapted to sustain a high pressure may be used.

The boiler B, in which the steam is maintained at an ordinary pressure of, for instance, from four to six atmospheres, is or may be heated by the combustion-gases from boiler A, which can be conducted either around the said boiler or into a flue, Q, by means of the valve O. The boiler B may, however, have a grate of its own.

The reservoir S is provided with two valves, a and b. The former allows the steam to pass into the suction-pipe i of the injector Z and prevents any accidental access of high-pressure steam into the reservoir. The valve b serves to regulate the pressure in S, and has therefore to be loaded to the degree of pressure required, which, according as the engine is provided with a condenser or not, is kept at a fractional part of an atmosphere, or somewhat above the atmospheric pressure.

For the purpose of utilizing the heat given off by the walls of the said reservoir, the same may be fitted with a water-jacket, in which the feed-water supplied by pump M is heated, this water being thereupon conducted to boiler A by pipe R; or the reservoir may be covered by a clothing of bad conductors of heat.

The feed-water, when not circulating through the jacket of the reservoir, may be heated by a special apparatus, X, Fig. 2, into which the steam passing off from S is directed.

The injector Z has to be regulated by its cocks c and d, or by any other suitable device, in such a manner that the amount of steam supplied by pipe H, together with the steam which may be generated in B is, as nearly as possible, equal to the quantity consumed by the engine. The evaporation in B is, however, of entirely subordinate importance as long as the supply from A and S balances the consumption in the engine; but whenever variations in the supply or in the expenditure of steam occur, and in consequence thereof the pressure in B decreases or increases, the large quantity of water in this boiler (which is of a temperature corresponding with the normal working pressure) serves in the one case to make up for the deficiency by generating an additional quantity of steam under the decreased pressure, or in the other case by condensing the surplus quantity, which is of a temperature above the mean. For contributing to the regulation of the steam-pressure in B this boiler may, however, be provided with suitable armatures, such as a self-acting apparatus operated upon by the steam-pressure, and serving to regulate the valve O. Moreover, the steam-spaces of the two boilers may be connected with each other by a pipe, in which a pressure-regulator is inserted for al-

lowing steam to pass from A into B whenever the pressure in B becomes too low.

Considering that in the ordinary course of working the evaporation in B is insignificant, and that, besides, a certain quantity of water is almost invariably carried over with the steam from A, the boiler B does not require to be regularly supplied with feed-water; but to make up for any lack a communication may 10 be established between the water-spaces of the two boilers by a pipe, t, having a cock or a valve, T, fitted to it for the purpose of regulating the amount of water which is to pass from A to B.

15 If it should be preferred, the feed-water may first be introduced into the boiler B, and thence forced by a special pump into it.

When the described system is to be applied to engines with intermittent motion, such as 20 direct-acting pumping-engines, the injector should be provided with a suitable contrivance for causing it to operate during the actual working periods of the engine only.

The following considerations will show the 25 advantages of our invention: When steam of very high pressure, such as may be generated in a so-called "safety-boiler," is utilized directly and expansively in a steam-engine, the heat of the steam decomposes the lubricating 30 material and burns the packings, in consequence whereof the wear on the cylinder, the piston, and other parts is excessive, and leakage of the stuffing-boxes, &c., unavoidable. Moreover, the strength of the parts of the engine having to be in proportion to the initial 35 pressure of the steam, the whole engine becomes very heavy and bulky.

In an engine of our system the high-pressure steam is utilized quite as efficiently as in 40 an expanding steam-engine. The work which the steam from boiler A has to perform in drawing waste steam from the reservoir S is fully compensated by the increase in the quantity of operative steam thus obtained, which increase is in proportion to the difference of 45 pressure in A and B, (supposing all other conditions to be alike.) The system consequently allows the full advantages to be realized which the use of high-pressure steam presents with 50 regard to consumption of fuel, but without being subject to the inconveniences connected with the direct introduction of such steam into the cylinder. The system also presents advantages with regard to security against danger from explosion otherwise connected with 55 high-pressure boilers sufficiently capacious to contain the quantity of steam and water required for a uniform working of the engine.

The boiler A, when belonging to the class of 60 boilers called "sectional" or "tubular" safety-boilers, is secure by its construction, whereas the boiler B, whose contents of water and steam is to compensate for the unavoidable deficiency in A, is neither exposed to a high 65 pressure nor to any material wear by the mode of heating the same.

If it should be preferred, the injector may be replaced by any other apparatus adapted to draw waste steam from S and to deliver it into B, and which is worked by steam issuing from A and exhausting into B.

Although for the system of engine described only a part of the waste steam can be reutilized, the entire quantity exhausted from the cylinder D may nevertheless be returned to 75 the boiler B in case a part of the steam from the latter is employed for other purposes.

Instead of combining together but one boiler of either class with a single steam-cylinder, and with one injector or other equivalent apparatus and one steam-reservoir, two or more of any or all of these parts may be used, and the different cylinders may belong to one or to different engines. For certain purposes— 80 as, for instance, in locomotive-engines—it may 85 also be advantageous to combine a high and a low pressure boiler in one construction.

The described invention is an improvement upon a former invention for which patents were granted to two of us—namely, to K. W. 90 Jurisch and J. H. Lewis—in England, on the 14th September, 1877, and in Germany on the 4th January, 1878, the present improvement consisting, essentially, in the introduction of the reservoir S, and also in the application of 95 the injector Z, or any other equivalent device, instead of the steam-compressing cylinder of the former invention. By using the said reservoir, into which the engine exhausts, an automatic and more uniform regulation of the 100 pressure of the waste steam from D is obtained than by the former arrangement, which requires a special and very complicated construction of slide-valve for causing a part of the steam from D to pass directly into the 105 steam-compressing cylinder and partly into the outer air or a condenser.

We claim as our invention—

The combination of the high-pressure steam-generator A, the low-pressure boiler B, cylinder D, reservoir S, and injector Z, the generator and receiver being connected directly to the boiler through the injector, the boiler with the cylinder, and the cylinder with the receiver, and the whole arranged as herein described, for the purpose set forth.

In testimony whereof we have signed our names to this specification in the presence of the subscribing witnesses.
